ATTORNEY

UNITED STATES PATENT OFFICE.

WILLIAM S. WELLS, OF BETHLEHEM, PENNSYLVANIA.

LOOM.

Application filed April 14, 1923. Serial No. 632,070.

To all whom it may concern:

Be it known that I, WILLIAM S. WELLS, a citizen of the United States, residing at Bethlehem, in the county of Lehigh and 5 State of Pennsylvania, have invented certain new and useful Improvements in Looms, of which the following is a specification.

This invention relates to looms, and it 10 consists in a loom having means to hold stretched the warp and woven cloth, means to hold the warp threads converging in plan toward the cloth, and a comb to beat up the filling introduced into sheds formed in the 15 warp, said comb being confined to move through and in angular relation to the plane which the stretched warp and cloth tend to assume and to and from the fell of the cloth with its dents intermeshing with 20 the warp threads and having said dents converging longitudinally thereof toward the line across them where they have impact with the fell of the cloth. The invention is designed especially for the weaving of fabric 25 from asbestos or the like strands which are quite thick but have very little tensile strength and resistance to abrasion, so that when it is attempted to weave this material in ordinary looms the warp is worn away by 30 the reed and as an incident of the shedding operation causing the warp threads to abrade each other and the weft forms such a bulky package that too frequent replenishment of the filling carrier is required. While the 35 essentials of the invention are those stated above, in practice a loom embodying the invention will of course include a carrier for the filling or weft and provision for forming the sheds, the latter in the example 40 herein illustrated and described being constituted by the second of the aforesaid means, which is formed as two harness frames arranged to move reversely to each other up and down.

45 In the drawings,

Fig. 1 is a side elevation of a loom embodying the invention; and

50 Figs. 2 and 3 are plan views, partly in section, of the forward part of the loom, showing certain parts in two different positions.

a is the loom frame. The said means to hold stretched the warp *A* and cloth *B* includes the front and rear cross-bars *b* and

c and any suitable take-up means *d* and let-off means *e*. The filling or weft-carrier is shown at *f*, *f'* being its guide for the weft *C*.

The said means to hold the warp threads *a* converging toward the cloth consists of frames *g* which move up and down in fixed 60 guides *h* and have upright dents *g'* spaced apart appreciably further than the warp threads are in the cloth, eyelets for the warp threads being afforded between these dents by pairs of spaced, preferably grooved, 65 guides *g''* rigidly connecting them, as by being soldered thereto.

The said comb consists of a support (here a bar) *o*, which is journaled in the loom frame close to the fell *x* of the cloth and in 70 the present case beneath it, and dents *p* each having one end set fast in the bar and the other end free. The comb has a crank *q* to which any suitable means for oscillating it 75 may be attached. The dents, when the comb is oscillated from the position of Fig. 1 or Fig. 2 to that of Fig. 3 (where they stand upright, abutting the fell *x*), intermesh with the warp threads. Furthermore, they converge from their free ends toward the line 80 where, when thus abutting the fell, they have impact with the latter.

In the preferred form the spacing of the dents along the line of their impact with the fell is substantially the same as that 85 of the warp threads in the cloth *B* and of their free ends substantially the same as the threads of the warp *A* in the transverse line where the free ends of the dents enter and leave the warp as the comb rises and falls. 90 The comb is set so that its dents will enter and leave the warp with as little contact therewith as possible.

Of course the warp threads are arranged to converge toward the fell of the cloth (or 95 rather diverge therefrom) for the purpose of avoiding their being abraded by each other in their up and down movements incident to shedding. By converging the dents of the comb in the way stated and properly 100 directing its course back and forth through the warp *A* can attain movement thereof with substantially no contact of the comb with the warp threads. Its course of movement may be directed in different ways, but 105 in point of simplicity and smoothness and reliability in action I find it best to pivot the reed with its axis of motion out of (as

below) and close to the plane in which the cloth and warp tend to stand stretched, and in that case whatever the position of the comb there will be a desirable focusing of its 5 dents toward substantially the same line (the fell) as that toward which the warp threads focus. Moreover, the extent of possible rubbing of the warps lengthwise thereof on each 10 back and forth movement of the beating up medium may be much less in the case of my comb (especially when pivotally movable) than in the case of the ordinary reed. Again, since the movements of the beating-up 15 medium in my construction have nothing to do with circumscribing the dimensions of the filling carrier, which may be arranged to move always through the widest part of the shed, the filling or weft package may be of considerably greater capacity than in ordinary 20 looms.

Having thus fully described my invention, what I claim as new and desire to secure by Letters Patent is:—

1. A loom including means to hold stretched the warp and woven cloth, means 25 to hold the warp threads converging in

plan toward the cloth, and a comb to beat up the filling introduced into sheds formed in the warp, said comb being confined to move through and in angular relation to the plane 30 which the stretched warp and cloth tend to assume and to and from the fell of the cloth with its dents intermeshing with the warp threads and having said dents converging longitudinally thereof toward the line across 35 them where they have impact with the fell of the cloth.

2. A loom including means to hold stretched the warp and woven cloth, means to hold the warp threads converging in plan 40 toward the cloth, and a comb to beat up the filling introduced into sheds formed in the warp, said comb extending transversely of said plane and being pivoted on an axis substantially parallel with and close to the fell 45 of the cloth to move through said plane with its dents intermeshing with the warp threads and having said dents converging longitudinally thereof toward the line across them where they have impact with the fell. 50

In testimony whereof I affix my signature.

WILLIAM S. WELLS.
